UNITED STATES PATENT OFFICE.

JULIUS EDUARD REINECKER, OF CHEMNITZ, GERMANY.

TOOL-GRINDING MACHINE.

SPECIFICATION forming part of Letters Patent No. 355,414, dated January 4, 1887.

Application filed April 17, 1885. Serial No. 162,550. (No model.)

To all whom it may concern:

Be it known that I, JULIUS EDUARD REINECKER, residing at Chemnitz, in the Empire of Germany, have invented a new and Improved Tool-Grinding Machine, of which the following specification is a full, clear, and exact description.

My invention relates to a tool-grinding machine; and it consists in the arrangement of the support for the tool, whereby the edges to be ground are made to receive the required degree of inclination.

In the accompanying drawings, Figure 1 represents a vertical section of the machine embodying my invention. Fig. 2 shows an enlarged view of the grinding-tool in section and outside view of part of a milling-cutter. Fig. 3 represents the grinding-tool applied in a straight or taper reamer. Fig. 4 is a horizontal section at line *x* *x*, Fig. 1. Fig. 5 is a horizontal section at line *y* *y*, Fig. 1. Fig. 6 is a vertical section of casing for spring-bolt *z*. Fig. 7 is an end view of the eccentric-bolt *k*.

The cutting tool or wheel is attached to the end of a spindle, *w*, and receives from the same its usual revolutions. This cutting-wheel consists of a ring, *r*, provided either with a back, *r'*, through which it is attached to the spindle, or it may be secured to the same in any other manner.

g *h* are the supports, upon which a support, *u*, is arranged in the usual manner, capable of receiving a longitudinal horizontal motion. The support *u* is secured to the support *h* through the bolt *i*, in the upper end of which a pin, *k*, being shaped eccentric at the part *k'*, (see Fig. 7,) where it works in the bolt *i*, is fitted. By turning this pin *k* either in one or the other direction the support *u* will be clamped securely to the support *h* or loosened, so as to be able to be moved in any desired position. The bolt *i* works in a longitudinal groove in the support *h*.

The upper surface of the support *u* is inclined at an angle corresponding to the necessary inclination of the surface to be ground with the cutting-edge of the tool. Upon this surface a support, *o*, is fitted, carrying a boss, *o'*, in which a sleeve, *n*, is supported, capable

of turning freely in the same, and secured in 50 said boss *o'* by nuts *o''*. (See Fig. 4.)

The support *o* is secured to the support *u* through the bolt *l*, fastened in the support *u*, and provided with the nut *m*. Around the bolt *l* the support *o* can be turned, and is then firmly secured in the desired position by said nut *m*. In the sleeve *n* a bolt, *p*, is fitted, upon the outer end of which the milling tool or wheel, *v*, to be ground is supported. Through the bolt *p* a pin, *q*, screwed into the end of 60 the sleeve *n* is arranged, the head of which forces the collar *p'* tight against the hub of the wheel *v*, and thus secures the same tight upon the bolt *p*, at the same time allowing said wheel to turn with the bolt *p*. The upper 65 part of the bolt *l* carries an arm, *t*, in the end of which a spring-bolt, *z*, (see Figs. 1 and 6,) is arranged, bearing upon the top of the wheel *v*, so as to hold the same in any desired position.

By the above-described arrangement of the supports the desired and necessary inclination of the surface, *d'*, to be ground, Figs. 2 and 3, to the cutting-edge *d* *d* will always be insured, and as the center line of the bolt *p* is parallel 75 with the inclined surface on top of support *u* only the turning of the support *o* ninety degrees around the bolt *l*, when operating on straddle milling-cutters, will insure the same 80 inclination of the grinding-surface to the cutting-edge on all three sides of the cutter without any alteration to the machine.

When operating on broaches, straight or tapering reamers, centers for supporting this class of work must be substituted for the boss 85 *o'* on the support *o*. By the arrangement of a ring or hollow cylinder, *r*, in place of a solid emery-wheel, and employing its face as the grinding-surface, I prevent the wearing of ridges in the grinding-surface, as every part 90 of the same will in nearly every case be employed and used, and all danger will be prevented from coming in contact with an adjoining cutting-surface of the tool under operation.

I claim as my invention—

1. The combination of support *u*, having inclined face and carrying support *o*, with pin

q and bolt *p*, for clamping tool *v*, and with bolts *i k* and support *h*, substantially as specified.

2. The combination of support *u* with support *o*, bolt *l*, arm *t*, spring-bolt *z*, and with a hollow cutter-wheel, *r*, to constitute a grinding-machine, substantially as specified.

In testimony whereof I have signed my name to this specification in the presence of two subscribing witnesses.

JULIUS EDUARD REINECKER.
